Application August 10, 1944, Serial No. 548,837

7 Claims. (Cl. 181—53)

1

This invention relates generally to mufflers or silencers, and more specifically to devices of this type adapted particularly for use in silencing the noises resulting from the operation of internal combustion engines, the predominant object of the invention being to provide a muffler of the type mentioned which, because of its improved construction and arrangement, is capable of performing its intended function in an improved and highly efficient manner.

Fig. 1 is a longitudinal section of the improved muffler of the present invention.

Fig. 2 is a cross-section taken on line 2—2 of Fig. 1.

Fig. 3 is a cross-section taken on line 3—3 of Fig. 1.

Fig. 4 is a cross-section taken on line 4—4 of Fig. 1.

Fig. 5 is a plan view of the improved muffler on a reduced scale.

In the drawing, wherein is shown for purposes of illustration, merely, one embodiment of the invention, A designates the improved muffler generally. The muffler A comprises an outer shell 1 which preferably is tapered and curved longitudinally, so as to minimize the resistance of air to the muffler when same is in motion on a moving motor vehicle. At the gas inlet end of the muffler, where the outer shell 1 is of substantially greater diameter than it is at the opposite, gas discharge end of said muffler, the shell 1 is provided with an end wall 2 which preferably is curved as is shown to good advantage in Fig. 1. The outer shell 1 is provided with a transverse wall 3 which is spaced longitudinally of said outer shell with respect to the end wall 2, said end wall 2, transverse wall 3, and the wall of the outer shell 1 providing a chamber within the outer shell.

The end wall 2 has formed therethrough a centrally-located opening through which is extended an inner, gas-inlet tube 4, said inner, gas-inlet tube being projected outwardly beyond the end wall 2 a slight distance, and being extended longitudinally through the chamber between said end wall 2 and the transverse wall 3, and abutting against said transverse wall 3 so that the rear end of said inner, gas-inlet tube is closed by said transverse wall 3. Also, disposed within the chamber between the end wall 2 and the transverse wall 3 is an intermediate tube 5 which is of substantially greater diameter than the inner, gas-inlet tube 4 and which embraces said inner, gas-inlet tube 4. The opposite ends of the intermediate tube 5 abut against the end wall 2 and

2

the transverse wall 3, respectively, whereby said opposite ends of said intermediate tube are closed by said end wall and said transverse wall.

Because of the arrangement of the inner, gas-inlet tube 4 and the intermediate tube 5 within the outer shell as just described, an annular chamber 6 is provided between the walls of said inner, gas-inlet tube and said intermediate tube, and an annular chamber 7 is provided between 10 the wall of said intermediate tube and the wall of the outer shell. The inner, gas-inlet tube 4 has formed through the wall thereof a multiplicity of apertures 8. These apertures are spaced circumferentially and longitudinally of the inner, 15 gas-inlet tube 4, with the apertured portion of the inner, gas-inlet tube starting at a point which is spaced inwardly of the end wall 2 some distance, and ending at a point which is spaced some distance from the transverse wall 3, as is shown in Fig. 1. Also, in order to obtain a substantial uniform flow of gases through the apertures throughout the entire length of the apertured portion of the inner, gas-inlet tube 4, the spacings of the apertures are gradually decreased in 20 the direction of the flow of the gases flowing through the inner tube 4 so that the density of the apertures is gradually increased in said direction of the flow of gases through said inner, gas-inlet tube. The intermediate tube 5 is provided with apertures 9 which are formed through 25 the wall thereof only at the extreme front end of said intermediate tube, and, also, the transverse wall 3 has formed therethrough apertures 10 which are arranged as is shown in Fig. 2 and 30 which communicate only with the annular chamber 7 of the muffler A.

Disposed within the shell 1 of the muffler A, adjacent to the transverse wall 3, is a second transverse wall 11, said transverse walls 3 and 40 11 being spaced apart to provide a chamber 12 therebetween. Also, located within the shell 1 of the muffler at a point spaced longitudinally thereof with respect to the transverse wall 11 is a third transverse wall 13. The transverse wall 11 is dished, as is shown to good advantage 45 in Fig. 1, and extended from said transverse wall 11 to the transverse wall 13 is an inner tube 14, said transverse wall 11 having formed centrally therethrough an opening which places the interior of the inner tube in communication with the chamber 12. The opposite end of the inner tube 14 abuts against the transverse wall 13 so that 50 said tube is closed by said transverse wall at said end thereof, and said inner tube 14 has formed through the wall thereof a multiplicity of aper-

tures 15 which are spaced circumferentially and longitudinally of said inner tube, the apertured portion of said inner tube starting at a point spaced rearwardly of the transverse wall 11 and ending at a point spaced forwardly from the transverse wall 13.

Arranged within the portion of the shell 1 of the muffler A, which is located between the transverse walls 11 and 13, is an intermediate tube 16 that is disposed in spaced, embracing relation with respect to the inner tube 14 so as to provide within said portion of said shell an annular chamber 17 between the walls of the inner tube 14 and the intermediate tube 16, and an annular chamber 18 between the wall of the intermediate tube 16 and the wall of the shell 1. Also, the wall of the intermediate tube 16 has formed therethrough apertures 19, which are located only at the extreme front end of said intermediate tube and which place the annular chamber 17 in communication with the annular chamber 18. It is to be noted that because of the streamlined shape of the shell 1 of the muffler A, the inner tube 14 and the intermediate tube 16 are tapered, with the larger diameters of said tubes being located at the transverse wall 11. In the case of the inner tube 14, the tapered shape thereof is important in that it provides for substantially uniform passage of gases through the apertures 15 thereof, throughout the entire length of the apertured portion of said inner tube, the arrangement of the apertures 15 being such that the desired uniform flow of gases is obtained.

The transverse wall 13 is provided with groups of apertures 20 which are formed therethrough in accordance with the arrangement illustrated in Fig. 4. These apertures place the chamber 18 in communication with a discharge chamber 21 that is located rearwardly of the transverse wall 13 and which is provided with an outlet conductor 22. In addition to the apertures 20 the transverse wall 13 is provided with an elongated, arcuate opening 23 which is formed therethrough at its bottom, as is illustrated in Fig. 4. This opening 23 is located immediately adjacent to a bottom portion of the wall of the shell 1, and serves a purpose to be hereinafter set forth.

In the operation of the muffler, exhaust gases, issuing from an internal combustion engine with which the muffler is associated for use, are discharged through the inner, gas-inlet tube 4 in the form of successive pressure pulsations and accompanying sound waves. The gases and sound waves pass through the multiplicity of apertures 8 in the wall of the inner, gas-inlet tube 4 into the annular chamber 6 and are thereby divided into a great number of parts. In the annular chamber 6 the direction of travel of the gases and sound waves is reversed, and each succeeding part of the many divided parts of gases and sound waves is caused to travel a longer distance to reach the apertures 9 of the intermediate tube 5, than a preceding part discharged into the chamber 6 through an aperture 8 of the inner, gas-inlet tube 4 which is located closer to said apertures 9. The gases and sound waves are again divided by passage through the apertures 9 and their direction of flow is again reversed, said gases and sound waves traveling rearwardly from the apertures 9 through the annular chamber 7 and pass through the apertures 10 in the transverse wall 3, into the chamber 12. From the chamber 12, the gases and sound waves travel rearwardly through the inner tube 14 and pass

through the apertures 15 of said inner tube into the annular chamber 17, said gases and sound waves again being broken up into many parts whose direction of travel is reversed, and said many parts of the gases and sound waves are compelled to travel various distances to reach the apertures 19 at the front end of the intermediate tube 16, as has been previously explained herein in connection with the discharge of gases and sound waves into the space 6 through the apertures 8 of the inner, gas-inlet tube 4. Upon passing through the apertures 19 into the annular chamber 18 the gases and sound waves are divided into a number of parts and their direction of travel is again reversed, said gases and any remaining modified sound waves finally passing through the apertures 20 and the arcuate opening 23 of the transverse wall 13 into the chamber 21, and being discharged from said chamber 21 through the outlet conductor 22 to atmosphere.

In the use of the improved muffler disclosed herein, the breaking up of the gases and the accompanying sound waves into many parts, and the forcing of the various divided parts of the gases and sound waves to travel various distances in the annular chambers 6 and 17, as has been explained, together with the repeated reversal of the direction of flow of the gases and sound waves, has a very effective silencing effect on the sound waves which causes the muffler to perform its intended function in a highly efficient manner.

The function of the elongated, arcuate slot 23, which is formed in the transverse wall 13 of the muffler, is to provide for ridding the interior of the muffler of moisture which may result from condensation of gases passing through the muffler. It is to be noted that this elongated slot is at the extreme lower end of the transverse wall 13, and that the outlet conductor 22 is located at the bottom of the discharge chamber 21, and as a result of such arrangement any condensate which accumulates in the lower portion of the annular chamber 18 will be blown therefrom by the force of the gases being exhausted from the muffler through the outlet conductor 22. Additionally, if any condensate should be produced within the annular chamber 1 it will be carried along with the gases passing through the muffler, such condensate passing through the apertures 10 of the transverse wall 3 into the chamber 12, and through the inner tube 14, and the apertures thereof, into the annular chamber 17, and then into the annular chamber 18, from which the condensate is discharged as explained above. The possible presence of condensate within the muffler is the reason for the dished formation of the transverse wall 11, as by so shaping said transverse wall 11 sharp corners are avoided, and a curved surface is provided along which the moisture may be forced by the gases to the entrance of the inner tube 14. If desired the transverse wall 3 may be provided at its bottom with an opening 10' through which condensate may pass from the annular space 1 to the chamber 12.

The improved muffler may be assembled in various ways, one of which is to assemble, exteriorly of the outer shell 1, the unit comprised of the transverse wall 11, the transverse wall 13, the inner tube 14, and the intermediate tube 16, these parts being preferably welded together in their assembled relation. The unit so assembled is passed into the open, larger end of the outer shell, the outer edge of the transverse wall

13 being forced into tight, wedging engagement with the inner face of the wall of the outer shell 1. The outer edge of the transverse wall 11 is then welded to the inner face of the wall of the outer shell with the aid of an elongated gas torch which is passed into the outer shell from the open, larger end thereof. The unit comprised of the transverse wall 3, the end wall 2, the gas inlet tube 4, and the intermediate tube 5, is also assembled exteriorly of the outer shell 1, and the parts of said unit are welded together in their assembled relation. This unit is passed into the outer shell 1 from the open, larger end of said outer shell, the outer edge of the transverse wall 3 being forced into tight, wedging engagement with the inner face of the wall of the outer shell, and the outer edge of the end wall 2 is welded to the edge of the outer shell at the larger end of said outer shell.

10 While I have described my improved muffler as being well adapted for use in association with internal combustion engines, the invention is not limited to such use, but, instead, may be employed in various other situations where it is desired to modify and silence sound waves which accompany gases resulting from combustion and explosions.

I claim:

1. A muffler comprising an outer shell, a tapered gas inlet tube extended longitudinally within a portion of said outer shell, a tapered intermediate tube arranged in embracing relation with respect to said gas-inlet tube with the wall of said gas-inlet tube and the wall of said intermediate tube spaced apart to provide an annular space therebetween, the wall of said intermediate tube being spaced from the wall of said outer shell to provide an annular space therebetween, a wall extended transversely of said outer shell within same which closes said gas-inlet tube and said intermediate tube at corresponding ends thereof, the wall of said gas-inlet tube being provided with apertures formed therethrough throughout a substantial portion of the length of said gas-inlet tube, and the wall of said intermediate tube having apertures formed therethrough at one end only thereof, a chamber located at the side of said transverse wall opposite to the side thereof at which said gas-inlet tube and said intermediate tube are located, apertures formed through said transverse wall in such arrangement that said chamber is placed in communication with the annular space between the wall of said intermediate tube and the wall of said outer shell, and an outlet conductor for the muffler which communicates with said chamber.

2. A muffler comprising an outer shell of tapered formation, a tapered gas inlet tube extended longitudinally within a portion of said outer shell, a tapered intermediate tube arranged in embracing relation with respect to said gas-inlet tube with the wall of said gas-inlet tube and the wall of said intermediate tube spaced apart to provide an annular space therebetween, the wall of said intermediate tube being spaced from the wall of said outer shell to provide an annular space therebetween, a wall extended transversely of said outer shell within same which closes said gas-inlet tube and said intermediate tube at corresponding ends thereof, the wall of said gas-inlet tube being provided with apertures formed therethrough throughout a substantial portion of the length of said gas-inlet tube, and the wall of said intermediate tube having apertures formed therethrough at one end only thereof, a chamber located at the side of said trans-

verse wall opposite to the side thereof at which said gas-inlet tube and said intermediate tube are located, apertures formed through said transverse wall in such arrangement that said chamber is placed in communication with the annular space between the wall of said intermediate tube and the wall of said outer shell, and an outlet conductor for the muffler which communicates with said chamber.

3. A muffler comprising an outer shell of tapered formation, a tapered gas inlet tube extended longitudinally within a portion of said outer shell, a tapered intermediate tube arranged in embracing relation with respect to said gas-inlet tube with the wall of said gas-inlet tube and the wall of said intermediate tube spaced apart to provide an annular space of tapered shape therebetween, the wall of said intermediate tube being spaced from the wall of said outer shell to provide an annular space of tapered shape therebetween, a wall extended transversely of said outer shell within same which closes said gas-inlet tube and said intermediate tube at corresponding ends thereof, the wall of said gas-inlet tube being provided with apertures formed therethrough throughout a substantial portion of the length of said gas-inlet tube, and the wall of said intermediate tube having apertures formed therethrough at one end only thereof, a chamber located at the side of said transverse wall opposite to the side thereof at which said gas-inlet tube and said intermediate tube are located, apertures formed through said transverse wall in such arrangement that said chamber is placed in communication with the annular space between the wall of said intermediate tube and the wall of said outer shell, and an outlet conductor for the muffler which communicates with said chamber.

4. A muffler comprising an outer shell, a gas-inlet tube extended longitudinally within a portion of said outer shell, an intermediate tube arranged in spaced relation with respect to said gas-inlet tube with the wall of said gas-inlet tube and the wall of said intermediate tube spaced apart to provide an annular space therebetween, the wall of said intermediate tube being spaced from the wall of said outer shell to provide an annular space therebetween, a wall extended transversely of said outer shell within same which closes corresponding ends of said gas-inlet tube and said intermediate tube, the wall of said gas-inlet tube being provided with apertures formed therethrough throughout a substantial portion of the length of said gas-inlet tube, and the wall of said intermediate tube having apertures formed therethrough at one end only thereof, a second transverse wall spaced within said outer shell from the first-mentioned transverse wall to provide a chamber therebetween and the first-mentioned wall being provided with apertures formed therethrough which place said chamber in communication with the annular space between the wall of said intermediate tube and the wall of said outer shell, a third transverse wall arranged within said outer shell in spaced relation with respect to the second-mentioned transverse wall, a primary tube disposed within the outer shell in the space between the second-mentioned and the third-mentioned transverse walls and communicating at one of its ends with said chamber, a secondary tube arranged in embracing relation with respect to said primary tube with the walls of said primary tube and said secondary tube spaced apart to provide an annular space therebetween, the wall of said secondary

tube being spaced from the wall of said outer shell to provide an annular space therebetween, said primary tube having apertures formed through the wall thereof throughout a substantial portion of the length of said primary tube, and the wall of said secondary tube having apertures formed therethrough at one end only thereof, and an exhaust compartment formed at the side of said third-mentioned transverse wall opposite to the side thereof at which said primary and secondary tubes are located, said third-mentioned transverse wall closing corresponding ends of said primary and secondary tubes and having apertures formed therethrough which places said exhaust compartment in communication with the annular space between the walls of said secondary tube and said outer shell.

5. A muffler comprising an outer shell, a gas-inlet tube extended longitudinally within a portion of said outer shell, an intermediate tube arranged in spaced relation with respect to said gas-inlet tube with the wall of said gas-inlet tube and the wall of said intermediate tube spaced apart to provide an annular space therebetween, the wall of said intermediate tube being spaced from the wall of said outer shell to provide an annular space therebetween, a wall extended transversely of said outer shell within same which closes corresponding ends of said gas-inlet tube and said intermediate tube, the wall of said gas-inlet tube being provided with apertures formed therethrough throughout a substantial portion of the length of said gas-inlet tube, and the wall of said intermediate tube having apertures formed therethrough at one end only thereof, a second transverse wall spaced within said outer shell from the first-mentioned transverse wall to provide a chamber therebetween and the first-mentioned wall being provided with apertures formed therethrough which place said chamber in communication with the annular space between the wall of said intermediate tube and the wall of said outer shell, a third transverse wall arranged within said outer shell in spaced relation with respect to the second-mentioned transverse wall, a primary tube disposed within the outer shell in the space between the second-mentioned and the third-mentioned transverse walls and communicating at one of its ends with said chamber, a secondary tube arranged in embracing relation with respect to said primary tube with the walls of said primary tube and said secondary tube spaced apart to provide an annular space therebetween, the wall of said secondary tube being spaced from the wall of said outer shell to provide an annular space therebetween, said primary tube having apertures formed through the wall thereof throughout a substantial portion of the length of said primary tube, and the wall of said secondary tube having apertures formed therethrough at one end only thereof, and an exhaust compartment formed at the side of said third-mentioned transverse wall opposite to the side thereof at which said primary and secondary tubes are located, said third-mentioned transverse wall closing corresponding ends of said primary and secondary tubes and having apertures formed therethrough which places said exhaust compartment in communication with the annular space between the walls of said secondary tube and said outer shell, and said third-mentioned transverse wall being provided with an opening at its bottom through which condensate may pass from said annular space between the walls of said secondary tube and said outer shell to said exhaust compartment for discharge from the muffler.

6. A muffler comprising an outer shell, a gas-inlet tube extended longitudinally within a portion of said outer shell, an intermediate tube arranged in spaced relation with respect to said gas-inlet tube with the wall of said gas-inlet tube and the wall of said intermediate tube spaced apart to provide an annular space therebetween, the wall of said intermediate tube being spaced from the wall of said outer shell to provide an annular space therebetween, a wall extended transversely of said outer shell within same which closes corresponding ends of said gas-inlet tubes and said intermediate tube, the wall of said gas-inlet tube being provided with apertures formed therethrough throughout a substantial portion of the length of said gas-inlet tube, and the wall of said intermediate tube having apertures formed therethrough at one end only thereof, a second transverse wall of dished formation spaced within said outer shell from the first-mentioned transverse wall to provide a chamber therebetween and the first-mentioned wall being provided with apertures formed therethrough which place said chamber in communication with the annular space between the wall of said intermediate tube and the wall of said outer shell, a third transverse wall arranged within said outer shell in spaced relation with respect to the second-mentioned transverse wall, a primary tube disposed within the outer shell in the space between the second-mentioned and the third-mentioned transverse walls and communicating at one of its ends with said chamber, a secondary tube arranged in embracing relation with respect to said primary tube with the walls of said primary tube and said secondary tube spaced apart to provide an annular space therebetween, the wall of said secondary tube being spaced from the wall of said outer shell to provide an annular space therebetween, said primary tube having apertures formed through the wall thereof throughout a substantial portion of the length of said primary tube, and the wall of said secondary tube having apertures formed therethrough at one end only thereof, and an exhaust compartment formed at the side of said third-mentioned transverse wall opposite to the side thereof at which said primary and secondary tubes are located, said third-mentioned transverse wall closing corresponding ends of said primary and secondary tubes and having apertures formed therethrough which places said exhaust compartment in communication with the annular space between the walls of said secondary tube and said outer shell, and said third-mentioned transverse wall being provided with an opening at its bottom through which condensate may pass from said annular space between the walls of said secondary tube and said outer shell to said exhaust compartment for discharge from the muffler.

7. A muffler comprising an outer shell, a gas-inlet tube extended longitudinally within a portion of said outer shell, an intermediate tube arranged in spaced relation with respect to said gas-inlet tube with the wall of said gas-inlet tube and the wall of said intermediate tube spaced apart to provide an annular space therebetween, the wall of said intermediate tube being spaced from the wall of said outer shell to provide an annular space therebetween, a wall extended transversely of said outer shell within same which closes corresponding ends of said gas-inlet tube

and said intermediate tube, the wall of said gas-inlet tube being provided with apertures formed therethrough throughout a substantial portion of the length of said gas-inlet tube, and the wall of said intermediate tube having apertures formed therethrough at one end only thereof, a second transverse wall spaced within said outer shell from the first-mentioned transverse wall to provide a chamber therebetween and the first-mentioned wall being provided with apertures formed therethrough which place said chamber in communication with the annular space between the wall of said intermediate tube and the wall of said outer shell, a third transverse wall arranged within said outer shell in spaced relation with respect to the second-mentioned transverse wall, a primary tube disposed within the outer shell in the space between the second-mentioned and the third-mentioned transverse walls and communicating at one of its ends with said chamber, a secondary tube arranged in embracing relation with respect to said primary tube with the walls of said primary tube and said secondary tube spaced apart to provide an annular

space therebetween, the wall of said secondary tube being spaced from the wall of said outer shell to provide an annular space therebetween, said primary tube having apertures formed through the wall thereof throughout a substantial portion of the length of said primary tube, and the wall of said secondary tube having apertures formed therethrough at one end only thereof, and an exhaust compartment formed at the 15 side of said third-mentioned transverse wall opposite to the side thereof at which said primary and secondary tubes are located, said third-mentioned transverse wall closing corresponding ends of said primary and secondary tubes and having apertures formed therethrough which places said exhaust compartment in communication with the annular space between the walls of said secondary tube and said outer shell, said outer shell, said primary tube, and said secondary tube being of tapered formation, and said annular spaces between the walls of said primary tube, said secondary tube and said outer shell being tapered.

CARL PETERS.
